REUBEN BRODER
BY
Joseph Blaeker
ATTORNEY

UNITED STATES PATENT OFFICE

REUBEN BRODER, OF NEW YORK, N. Y.

PICTURE HANGER

Application filed March 20, 1930. Serial No. 437,532.

This invention relates to improvements in hangers used for suspending pictures, mirrors, tapestries and the like from walls, one object being to provide a simple and inexpensive locking device embodied in and cooperating with the hook-shaped portion of the hanger to prevent the accidental disengagement of the hanger from the picture molding.

Another object of this invention is to provide an ornamental device for concealing the hanger proper, and integrally connected to and forming a convenient means for operating the hanger locking device.

Another object of this invention is to provide a picture hanger comprising a hook shaped member and a cooperating and detachable member which functions as a picture hanger locking device, the said detachable member being adapted to be locked in a predetermined position in the hook-shaped member.

Another object of this invention is to provide a picture hanger which may be used either on a picture molding or on a nail screw or hook driven into a wall, all of the said hanging means being in the rear of the hook shaped portion of the hanger and concealed from view, and the nail receiving means being in the lower end of the hanger.

With these and other objects in view, the invention resides in the arrangement and combination of the parts, the essential features of which are hereinafter fully described, are particularly pointed out in the appended claims and are illustrated in the accompanying drawings, in which:

Figure 1 is an edge view of my improved picture hanger and picture hanger locking device as it appears when mounted in position on a molding, the hanger being partly in section.

Figure 2 is a rear view of the assembled picture hanger.

Figure 3 is a perspective view of the hook-shaped portion of the picture hanger as it appears when hung on a nail; the front face having an aperture for the picture hanger locking device.

Figure 4 is a perspective view of an elongated snap fastening means forming the male member of the hanger locking device.

Figure 5 shows a fragment of the hook-shaped portion of the hanger, comprising a modified aperture which serves to fix the position of the hanger locking device.

Figure 6 shows a fragment of the hook-shaped portion of the hanger, comprising a modified aperture which serves to prevent the hanger locking device from falling out or becoming disengaged.

In the illustrated embodiment of the invention, my improved picture hanger is made of two parts, a hook-shaped hanger 1 and a rosette 2 attached to form a cooperating unitary article of manufacture.

The body portion 3 of the hanger 1 has an upper hook 4 to engage a picture molding. The lower end of the body portion 3 has a hook 5 to engage a picture or mirror cord 6 of circular cross section. The hook 5 is inwardly bent to embrace and clamp the cord 6, and has a straight end portion 7 substantially parallel with the body portion 3 of the hanger 1. The straight portion 7 is provided with an aperture 8 which consists of a lower enlarged portion 9 and a smaller upper portion 10. As best shown in Figure 2, the upper portion 10 of the aperture 8 is adapted to engage the back of the head of a nail after the head has been passed through the lower enlarged portion 9. At the bottom of the hook 5 there is provided a downwardly facing aperture 11 which serves to receive a cord (not shown) which may be clamped within the said hook 5. This aperture 11 serves to support a picture hung on a single vertical cord in place of the cord 6. The upper hook 4 and the lower hook 5 are located on the same side of the body portion 3.

Secured to the outer face of the hanger 1 is the rosette or covering device 2 which is of a size sufficient to cover and hide the hanger, the rosette being preferably detachably secured to the hanger by means of a male fastening element or snap member 12, which permits replacement with other interchangeable rosettes. The molding 22 is of a type generally provided near the ceiling of a room. The picture hangers are usually

loosely mounted on the moldings and in no way fastened thereto. Due to the stiffness of the cord which is usually reenforced with wires, there is a tendency to throw the hanger off the molding while the picture is being adjusted on the wall. The picture hangers frequently become disengaged from the moldings thereby allowing the pictures to drop. To overcome this disengaging tendency, I have devised the simple expedient of elongating the snap member 12 to form a picture hanger locking member 13 which projects inwardly of the hanger just below the head bead 14 of the molding 22. This locking member 13 strikes the head bead 14 of the molding 22 when there is a tendency to displace the hanger therefrom and causes the hanger to remain in its proper position. The accidental disengagement of the hanger is thus eliminated. It is to be noted that the head bead 14 is circularly formed and accordingly the most effective point to strike the bead is at its vertical center line and the locking member or extension 13 is made long enough to reach substantially to the vertical center line of the head bead.

As best shown in Figure 4, the locking member 13 comprises two elongated substantially semi-circular resilient arms 15, 15, which have been extruded from a metal plate 16. This plate is preferably of circular form and has four right angularly bent spurs 17, 17, 17, 17, extruded therefrom, in a direction opposite to that of the locking member 13. The spurs are adapted to enter the woodwork of the rosette 2 and retain the plate 16 and the locking member 13 in concentric relation with the rosette.

The hanger 1 is shown in Figure 2 and Figure 3 as provided with a circular aperture 18 forming a female fastening element for the entrance of the male fastening element 12, and the locking member 13. A key 19 best shown in Figure 5, may however extend vertically into the aperture 18 to enter between the arms 15, 15 and prevent rotation of the rosette. Another modification is shown in Figure 6 where a key-way slot 20 extending downwardly from the aperture 18 is provided in which to press down the snap member 12 and prevent the rosette 2 and the locking member 13 from falling out of the aperture 18 and becoming disengaged from the hanger 1.

As shown in Figure 3, the hanger is supported on a nail 21 and the cord 6 is clamped in the lower hook 5 which is inwardly bent after the cord is inserted therein. It is to be noted that when the hanger is used without a rosette, that the aperture 18 may be omitted.

It is to be noted that while the upper and lower hooks are located as shown on the same side of the body of the hanger, that the lower hook may be bent on the opposite side of the

body and form a hanger having a shape substantially like the letter S.

It is thus readily seen that there has been provided a combined picture hanger and rosette provided with means to prevent their accidental disengagement from a molding and which are also provided with detachable mating fastening elements for retaining the picture hanger and rosette operatively associated. It is also readily seen that this picture hanger may be hung on a molding or on a nail either in combination with or without the rosette.

While I have described what I deem to be the most desirable embodiment of my invention, it is obvious that various changes may be made in the proportion and minor details of construction within the scope of the appended claims.

Having thus described my invention, I claim as new and desire to secure by Letters Patent:

1. A picture-hanger comprising a body having an upper supporting hook curved downwardly to engage a wall molding, a lower cord-supporting hook curved upwardly, the upper and lower hooks being located on the same side of the body, the said cord-supporting hook being inwardly bent and adapted to embrace and clamp a picture cord therein, and being also provided with a straight end portion having a nail-receiving aperture therein.

2. A picture hanger comprising in combination a body member having on one side thereof an upper supporting hook curved downwardly to engage a molding head bead, a lower cord-supporting hook curved upwardly, and an ornamental covering member detachably affixed on the other side of the said body member and having means penetrating through the body and extending beneath the molding head bead and forming a locking means for said picture hanger.

3. In combination, a picture hanger having an upper hook curved to engage a molding head bead, a device for covering said hanger provided with a projecting fastening element and adapted to enter an aperture in the body of said hanger, said element projecting therefrom and resting below the head bead so as to prevent accidental disengagement of the hanger from the molding.

4. In combination, a picture hanger having an upper hook engaging a molding head bead, a device for covering said hanger provided with a right-angular male fastening element integral with the covering device and adapted to enter an aperture in the body of said hanger to retain the hanger and cover operatively associated and penetrating through the body of the hanger and extending beneath the molding head bead so as to prevent accidental disengagement of the hanger from the molding, said male fastening element ex-

tending substantially to the center line of the head bead.

5. In combination, a picture hanger having an upper hook engaging a molding head bead, a device for covering said hanger provided with a male fastening element integral with the covering device and adapted to enter a female fastening element in the body of said hanger to retain the hanger and cover, said fastening elements being positioned beneath the molding head bead and one of said elements forming a locking means for said picture hanger.

10 6. In combination, a picture hanger comprising a body having an upper hook curved downwardly to engage a wall molding and a lower cord-supporting hook curved upwardly, a device for covering said hanger provided with a fastening element adapted to engage a 15 mating fastening element in the body of said hanger to retain the hanger and cover, said fastening elements being positioned beneath the molding head bead and one of said elements forming a locking means for said picture hanger.

20 25 Signed at New York, in the county of Bronx and State of New York, this 18 day of March, A. D. 1930.

REUBEN BRODER.
